UNITED STATES PATENT OFFICE.

CLARENCE I. ROBINSON, OF WEST NEW BRIGHTON, NEW YORK, ASSIGNOR TO STANDARD OIL COMPANY, OF BAYONNE, NEW JERSEY, A CORPORATION OF NEW JERSEY.

UTILIZING SULFUR-CONTAINING PETROLEUM.

1,018,374.

Specification of Letters Patent.

Patented Feb. 20, 1912.

Original application filed August 21, 1903, Serial No. 170,327. Divided and this application filed March 21, 1907. Serial No. 363,712.

To all whom it may concern:

Be it known that I, CLARENCE I. ROBINSON, a citizen of the United States, residing at West New Brighton, in the county of 5 Richmond and State of New York, have invented certain new and useful Improvements in Utilizing Sulfur-Containing Petroleum, of which improvements the following is a specification.

10 This invention relates more particularly to the utilization of a substantial part at least of the sulfur content of such petroleum as is obtained from the oil fields in the State of Texas, near the town of Beaumont, 15 in Jefferson county. Said petroleum is herein referred to as Beaumont oil or Beaumont petroleum for convenience of reference. These designations are each intended to include oil of the same or substantially similar 20 character wherever found or however obtained.

For the purpose of this specification, such 25 substantial similarity in character to the oil obtained near Beaumont is sufficiently shown for any crude oil by the fact that it responds to each of the two following tests, that is to say, first, the sulfur naturally present therein is given off (in utilizable proportion) in the form of hydrogen sulfid 30 when the crude oil is heated to between about 300° F. and about 500° F., and, second, on distilling the crude oil, with or without cracking, and on collecting by itself the fraction coming over between 250° F. 35 and 600° F., more or less, the so collected distillate, after treatment with sulfuric acid of 66° B. (in however large proportion) and subsequent washing with water and caustic soda lye (all in the known way) will smoke 40 badly when burned in the ordinary petroleum (kerosene) lamps. There may, however, be petroleum which is analogous to Beaumont oil in responding to the first of these tests; but which does not respond to 45 the second of them; and which consequently is not Beaumont petroleum as above defined. The invention extends to the utilization of such analogous petroleum as well as of that which is substantially similar to the oil 50 which is obtained near Beaumont, in Texas, in respect to both of the characteristics herein above mentioned.

So far as I am aware, naturally present sulfur has never been recovered in utilizable

form from any crude petroleum, although it 55 has long been known to be a common constituent of petroleum and to exist in considerable proportion in some varieties, as in the oil from the Lima, Ohio, and Ontario, Canada, fields, for example. The crude oil 60 from the Pennsylvania fields is nearly free from it. Beaumont crude oil contains, according to my experience, between one and two per cent of sulfur. The sulfur in Lima or Canadian oil is not utilizable as I have 65 found that of Beaumont petroleum to be. In distilling the former the quantity of sulfur in the still gases is too small to be of use; and it is besides evolved at such times and in such manner that it would be impracticable to utilize it were the quantity sufficient.

The utilizable sulfur in Beaumont petroleum I believe to exist therein in elementary state and to form hydrogen sulfid by its 75 combination at comparatively low temperatures with hydrogen of hydrocarbons, which are partially decomposed by the sulfur at such temperatures. This hydrogen sulfid comes off, as I have discovered, in large volume 80 during a short period and in such manner that it can be controlled without interfering with the running of the still. Some hydrogen sulfid is given off at all times in distilling crude Beaumont petroleum; but 85 what is evolved at other times is not utilizable as I have found that which comes off during said short period to be.

In accordance with the present invention Beaumont or analogous oil is heated in a 90 suitable still gradually to about 500° F., more or less, and the sulfur-containing gas which is given off during such rise of temperature (all, or part, as may be determined) is collected, conveyed away and oxidized 95 to form sulfuric acid. This oxidation is effected, first, by combustion in hydrogen sulfid burners, and, second, by subjection in lead chambers or contact apparatus to the agencies necessary to convert sulfur dioxid 100 into sulfuric acid. In this conversion, when it is accomplished in the lead chambers, the sulfur trioxid unites with water to form chamber acid which can then be concentrated in any known or suitable way. Should 105 the conversion be accomplished in contact apparatus, the sulfur trioxid may remain free as sulfuric anhydrid (which is regarded

in this specification as anhydrous sulfuric acid) or it may be combined with water and so constitute hydrated sulfuric acid of greater or less concentration, fuming or non-
5 fuming, as may be desired. Before the combustion in hydrogen sulfid burners, the gas should be freed from oil vapors by cooling. Said combustion results in the formation of water as well as of sulfur dioxid; and said
10 water may be removed or not before the oxidation of the sulfur dioxid to sulfuric acid, according to the case. Further, in accordance with the invention, should it be desired to utilize the sulfur-containing gas
15 from Beaumont or analogous crude oil otherwise than for the preparation of sulfuric acid, it can be done by subjecting said gas to any known or suitable procedure for the utilization of hydrogen sulfid. I believe that
20 I am the first to collect such gas for the utilization of the hydrogen sulfid therein.

The heating of the Beaumont oil to obtain the sulfur-bearing gas is best performed at temperatures as nearly constant as is consistent with a good evolution of the sulfur-containing gas. This evolution is most rapid at from about 400° F. to about 450° F. Especially, therefore, during this temperature interval should the fire be regulated to
25 preserve an even discharge of the gas. By regulating the fire with reference to the sulfur-containing gas, the formation of uncondensable hydrocarbons is reduced, so that, when the gas is burned, the combustion
30 products will contain but little carbonic oxid and dioxid, freedom from these substances being desirable for the subsequent conversion of the sulfur dioxid into sulfuric acid. The gas should be mainly hydrogen sulfid; and I have obtained it with a content
35 of more than 96% of this substance.

The gas commences to be evolved when the temperature of 300° F. is reached (as shown by a thermometer in the liquid in the still). The yield of utilizable gas will, in my experience, have become practically complete when 500° F. is reached. When the gas evolved becomes (or is at any time found to be) too poor in hydrogen sulfid or too much mixed
45 with uncondensable hydrocarbons to be satisfactorily utilizable, it may be delivered to a pipe line for burning under the still or be disposed of in any desired way. The heating of the Beaumont oil to obtain utilizable
50 sulfur-containing gas can (and most advantageously does) form part of the distillation for obtaining the burning oil (kerosene) distillate.

Any suitable apparatus can be used to
60 carry out the present invention. The accompanying drawing is a diagram of such an apparatus. This I have also invented; but in consequence of official requirement of division I have included it in the subject-
65 matter of application No. 363,713, filed by

me on March 21, 1907, as a division and continuation of my application of August 21, 1903, No. 170,327 and in part also as a continuation of my application of the same date No. 170,326. Patent 968,692 was granted 70 August 30, 1910, on my said application No. 170,327 and patent 1,014,520 on January 9, 1912, on my said application No. 170,326. The present application is a division and continuation of my said application No. 75 170,327 and has been made in consequence of official requirement of division.

The following is a description of what is considered the best mode of carrying the invention into effect. Additions, omissions 80 and other modifications can be made indefinitely so long as the substance of any one or more of the hereinafter written claims is taken.

The crude Beaumont petroleum is supplied after the usual manner to the crude oil still *a* by a charging line *b*; and when the still has been filled to the desired level it is heated so as gradually to raise the temperature of the still's contents. The gas and 85 vapors as they are formed by the heat pass over to the condenser *c* wherein they are cooled to condense the oil vapors. The liquid of condensation flows into the distillate receiver *d*. The gas, including any uncondensed vapor, passes either by the line *e* to be burned as fuel or otherwise disposed of, or by the gas line *f* to be utilized in sulfuric acid making. While the temperature 90 of the vapors as they leave the still *a* is below about 500° F., more or less, the gas from the condenser *c* consists of about or above 85% hydrogen sulfid (ordinarily, if not always) and is then delivered to gas line *f*. The temperature is raised to this degree 100 more gradually than in ordinary distillation, being regulated with special reference to the production of hydrogen sulfid to the best advantage, and the distillate being allowed to take care of itself. It is specially 105 important to keep the temperature of the oil as nearly constant as is consistent with a good evolution of gas during the temperature interval from about 400° F. to about 450° F., during which interval the evolution 110 of hydrogen sulfid is most rapid. By proper regulation of the heating, the gas evolved will consist (as is desirable) of a larger proportion of hydrogen sulfid and a smaller proportion of uncondensable hydrocarbon 115 vapors than would otherwise be the case.

Should the hydrogen sulfid given off at any time below about 500° F. be found to be unsatisfactory in quantity or quality, it can be sent into line *e* as long as it may be so; but in my experience this change of gas line has not been found expedient until about 500° F. is reached. At about or above this degree the gas should be turned into the line *e*, so soon as the evolution of hydrogen sulfid fails 120 125 130

in quantity or quality, the line *f* remaining closed during the rest of the run.

While the temperature is rising toward 500° F., the distillate collects in the receiver *d* until it becomes too smoky for utilization without removal of smoky hydrocarbons therefrom beyond what can be accomplished by treatment with 66° B. acid and redistillation. This has been found in my experience to be when the gravity of the distillate at the worm end (that is, before it enters the receiver *d*) is about 42° B., more or less, the temperature of the vapors escaping from the still *a* being about 400° F., more or less. 10 The distillate then in the receiver is herein-after referred to as the first burning oil cut. It belongs to the lighter end of the burning oil fraction. It amounts, in my experience, to from five to ten per cent. of the crude oil supplied to still *a*. The inlet of receiver *d* is then closed and that of receiver *g* is opened, so that the distillate from condenser *c* will flow into this latter receiver. This 15 change of receiver has been effected, in my experience, before the yield of hydrogen sulfid becomes unsatisfactory; so that for a time after the change of receivers the heating of the still *a* is regulated with special reference to the evolution of hydrogen sulfid. 20 Afterward the heat of still *a* is regulated (as customary) with special reference to the distillate to be obtained.

The distillation is carried on with crack-ing which commences (in my experience) 25 when the temperature of the liquid oil in the still *a* is about 600° F., more or less, the distillate in the two receivers *d* and *g* then amounting to about 40%, more or less, of the crude oil supplied to the said still *a*. The 30 distillation is continued as long as it is safe to do so, say, till the distillate in said two receivers amounts to about 85% of said crude oil. The oil in receiver *g* is herein termed the cracked oil distillate; although 35 a large percentage is composed of uncracked products.

It is customary to have a receiver into 40 which the distillate can be turned whenever it becomes undesirable in quality, the result of something accidental; the receiver *h* is provided for such purpose. When necessary, its inlet can be opened, those of the receivers *d* and *g* being closed. Any one of the three receivers could be used for this 45 purpose, the other two serving to collect the first burning oil cut and the cracked oil distillate, respectively. After the completion of a run, the crude oil still *a* can be emptied through the tar line *j* or in any suitable way, 50 preparatory to refilling with crude oil for a new run.

The first burning oil cut and the cracked oil distillate may be disposed of as may be desired, the disposition made of them being 55 no part of the present invention.

The heating of the crude oil for purposes of the present invention can (as already indicated) be regarded as complete when the oil in distillation has attained a temperature of about 500° F.; at which time the supply of elementary sulfur therein will have become practically exhausted. The natural sulfur content of Beaumont petroleum is chiefly in the form of elementary sulfur; but it also includes some hydrogen sulfid and some sulfur containing hydrocarbons. Some sulfur containing hydrocarbons are believed also to be formed artificially during distillation of the oil. The naturally present hydrogen sulfid, of course, unites with that formed artificially. As hydrogen sulfid is soluble in hydrocarbon oils, a certain amount will appear in the distillate. The naturally present and artificially formed sulfur containing hydrocarbons are only to a small extent decomposed on distillation. They, therefore, for the most part either pass over with unsulfured hydrocarbons of like boiling points and are condensed with them as part of the distillate, or else (if of too high boiling point to pass over at the temperatures attained) remain in the residual oil. 70 75 80 85 90

So much of the gas from the crude still *a* as is allowed to enter the gas line *f* is conveyed thereby to a storage gasometer 3, from which it is supplied to the burner 4, wherein both it and other combustible substances present are burned, the hydrogen sulfid being converted thereby into sulfur dioxid and water. These may both be delivered 95 through gas line 5 into the lead chamber 6 for making sulfuric acid. They could be delivered into a Glover tower 7; but this is not considered desirable, in view of the large 100 proportion of water vapor in admixture with the sulfur dioxid. The water could, however, be separated by condensation and the sulfur dioxid, being heated, could be sent either into tower 7 or lead chamber 6. 105 It could be sent into other sulfuric acid making apparatus. 110

The dilute sulfuric acid from the lead chamber 6 is carried by line 16 to an apparatus wherein it is concentrated to any desired degree by heating or by adding sulfuric anhydrid or by the aid of both operations. It is delivered by acid line 18 to a storage tank 19 from which it can be discharged through line 20 for sale or use, as 115 120 may be desired.

The expression "operations for utilizing the sulfur content" in those of the herein-after written claims in which it occurs means one or more such operations and refers primarily to operations for converting the sulfur-containing compound into sulfuric acid; but it means also other known or suitable operations for utilizing said component. For example, hydrogen sulfid 125 130

can be burned and the resulting sulfur di-
oxid utilized in known or suitable ways for
producing sulfite and bisulfite salts, sulfur-
ous acid solution and other substances or
effects known to be producible by sulfur di-
oxid. Sulfur can be deposited by subjecting
hydrogen sulfid in known or suitable ways
to sulfur dioxid.

I claim herein as my invention or dis-
covery:

1. The process of making hydrogen sul-
fid, by heating sulfur bearing Beaumont or
analogous petroleum to temperatures at
which gas rich in hydrogen sulfid is evolved
therefrom, removing condensable hydrocar-
bon vapors from the so evolved gas, and col-
lecting the remaining gas appropriately for
subsequent subjection of the same to oper-
ations for utilizing the sulfur content of
said gas, substantially as described.

2. The process of making hydrogen sul-
fid, by heating sulfur bearing Beaumont or
analogous petroleum to between 300° F.
and 500° F., so as to evolve therefrom a gas
rich in hydrogen sulfid and suitably free
from non-condensable hydrocarbons, cool-
ing the so evolved gas to separate the con-
densable hydrocarbons from the non-con-
densable constituents, and collecting the gas
appropriately for subsequent subjection of
the same to operations for utilizing the sul-
fur content of hydrogen sulfid, substantially
as described.

3. The process of making hydrogen sul-
fid, by heating sulfur bearing Beaumont or
analogous petroleum to temperatures at
which gas rich in hydrogen sulfid is evolved
therefrom, regulating said heating appropri-
ately for obtaining a steady stream of
good volume of non-condensable gas rather
than of hydrocarbons condensable as distil-
late, removing condensable hydrocarbon va-
pors from said gas, and collecting the gas
appropriately for subsequent subjection of
the same to operations for utilizing the sul-
fur content of said gas, substantially as de-
scribed.

4. The process of making hydrogen sul-
fid, by heating sulfur bearing Beaumont or
analogous petroleum to between 300° F.
and 500° F., so as to evolve therefrom a gas
rich in hydrogen sulfid and suitably free
from non-condensable hydrocarbons, cool-
ing the so evolved gas to separate the con-
densable hydrocarbons from the non-con-
densable constituents, regulating said heat-
ing appropriately for obtaining a steady
stream of good volume of the gas rather
than of the condensate formed by said cool-
ing, and collecting the gas appropriately for
subsequent subjection of the same to oper-
ations for utilizing the sulfur content of
hydrogen sulfid, substantially as described.

5. The process of making hydrogen sul-
fid, by heating sulfur bearing Beaumont or

analogous petroleum to gradually increas-
ing temperatures to evolve gas rich in hy-
drogen sulfid therefrom, cooling the so
evolved gas to separate the condensable hy-
drocarbons from the non-condensable con-
stituents, collecting the gas appropriately
for subsequent subjection of the same to op-
erations for utilizing the sulfur content of
hydrogen sulfid, and stopping such collec-
tion when the temperature of the so heated
petroleum is about 500° F., substantially as
described.

6. The process of utilizing Beaumont or
analogous petroleum, by heating such sul-
fur bearing petroleum to temperatures at
which gas rich in hydrogen sulfid is evolved
therefrom, removing condensable hydrocar-
bon vapors from the so evolved gas, col-
lecting the remaining gas, and subjecting
it to operations for utilizing the sulfur con-
tent of said gas, substantially as described.

7. The process of utilizing Beaumont or
analogous petroleum, by heating such sul-
fur bearing petroleum to between 300° F.
and 500° F., so as to evolve therefrom gas
rich in hydrogen sulfid and suitably free
from non-condensable hydrocarbons, cool-
ing the so evolved gas to separate the con-
densable hydrocarbons from the non-con-
densable constituents, collecting the gas, and
subjecting it to operations for utilizing the
sulfur content of hydrogen sulfid, substan-
tially as described.

8. The process of utilizing Beaumont or
analogous petroleum, by heating such sul-
fur bearing petroleum to temperatures at
which gas rich in hydrogen sulfid is evolved
therefrom, regulating said heating appropri-
ately for obtaining a steady stream of
good volume of non-condensable gas rather
than of hydrocarbons condensable as distil-
late, removing condensable hydrocarbon va-
pors from said gas, collecting the gas,
and subjecting it to operations for utilizing
the sulfur content of said gas, substantially
as described.

9. The process of utilizing Beaumont or
analogous petroleum, by heating such sul-
fur bearing petroleum to between 300° F.
and 500° F., so as to evolve therefrom a gas
rich in hydrogen sulfid and suitably free
from non-condensable hydrocarbons, cooling
the so evolved gas to separate the condens-
able hydrocarbons from the non-condensable
constituents, regulating said heating appropri-
ately for obtaining a steady stream of
good volume of the gas rather than of the
condensate formed by said cooling, collect-
ing the gas, and subjecting it to operations
for utilizing the sulfur content of hydro-
gen sulfid, substantially as described.

10. The process of utilizing Beaumont or
analogous petroleum, by heating such sul-
fur bearing petroleum to gradually increas-
ing temperatures to evolve gas rich in hy-

- drogen sulfid therefrom, cooling the so evolved gas to separate the condensable hydrocarbons from the non-condensable constituents, collecting the gas, subjecting it to 5 operations for utilizing the sulfur content of hydrogen sulfid, and stopping the subjection of the gas to said operations when the temperature of the so heated petroleum is about 500° F., substantially as described.
- 10 11. The process of separating certain sulfur and hydrocarbon constituents of Beaumont or analogous petroleum from each other, by heating such sulfur bearing petroleum to temperatures at which gas rich 15 in hydrogen sulfid is evolved therefrom, and regulating said heating appropriately for obtaining a steady stream of good volume of non-condensable gas rather than of condensable hydrocarbons, substantially as described.
12. The process of separating certain sulfur and hydrocarbon constituents of Beaumont or analogous petroleum from each other, by heating such sulfur bearing 20 petroleum to between 300° F. and 500° F., and regulating said heating appropriately for obtaining a steady stream of good volume of non-condensable gas rather than of condensable hydrocarbons, substantially as 25 described.
- 30 13. The process of separating certain sulfur and hydrocarbon constituents of Beaumont or analogous petroleum from each other, by heating such sulfur bearing petroleum to temperatures at which gas rich 35 in hydrogen sulfid is evolved therefrom, regulating said heating appropriately for obtaining a steady stream of good volume of non-condensable gas rather than of condensable hydrocarbons, and removing condensable hydrocarbon vapors from said gas, substantially as described.
14. The process of separating certain sulfur and hydrocarbon constituents of Beaumont or analogous petroleum from each 40 other, by heating such sulfur bearing petroleum to between 300° F. and 500° F., regulating said heating appropriately for obtaining a steady stream of good volume of non-condensable gas rather than of condensable hydrocarbons, and removing condensable hydrocarbon vapors from said gas, substantially as described.
